UNITED STATES PATENT OFFICE.

JOHN HAMERSLEY, OF NEW COMERSTOWN, OHIO.

REFRIGERATING APPARATUS.

1,104,665.

Specification of Letters Patent. Patented July 21, 1914.

Application filed October 7, 1911. Serial No. 653,893.

To all whom it may concern:

Be it known that I, JOHN HAMERSLEY, a citizen of the United States, residing at New Comerstown, in the county of Tuscarawas and State of Ohio, have invented new and useful Improvements in Refrigerating Apparatus, of which the following is a specification.

This invention relates to improvements in refrigerating apparatus and of systems of the absorption type, the object of the invention being to provide a refrigerating species, including a novel construction of receptacles used successively as stills and absorbers, and embodying a simple, reliable and efficient organization of parts insuring safety, economy and continuity of operation and flow of the gas to the absorption liquid without objectionable noise.

Reference is to be had to the accompanying drawings constituting a part of this specification, in which similar characters of reference denote corresponding parts in all the views, and in which—

Figure 1 is a side elevation of my apparatus, embodying my preferred manner of connecting the producing tanks. Fig. 2 is a vertical sectional view through one of the producing tanks. Fig. 3 is a plan view of the producing tank. Fig. 4 is a horizontal transverse sectional view taken substantially on the line 4—4 in Fig. 2, looking in the direction of the arrow. Fig. 5 is a fragmentary horizontal sectional view of one of the producing tanks and taken substantially on the line 5—5 in Fig. 2 to disclose in plan the siphon circulator. Fig. 6 is a fragmentary sectional view through one portion of the siphon circulator.

Referring more particularly to the various views, I provide a plurality of similar generating tanks 10, 11 mounted on platforms 10^a, 11^a, supported by suitable legs 10^b, 11^b respectively. The tanks 10 and 11 each consist of an outer casing 12 and an inner casing 13, the space between the outer casing 12 and the inner casing 13 constituting a water cooling chamber 14 and the space provided within the inner casing 13 constituting a producing chamber 15. A head 16 is positioned on each of the tanks 10 and 11 and each of the said heads are connected to the respective platforms 10^a, 11^a by longitudinally extending bolt rods 17, passing through each of the chambers 14 to

rigidly retain the tanks 10 and 11 on their respective platforms 10^a and 11^a.

Extending outwardly from the producing chamber 15 of the tank 10 is a high pressure pipe 18 and extending outwardly from the chamber 15 of the tank 11 is a similar high pressure pipe 18^a, the said pipes 18 and 18^a terminating in a high pressure pipe 19 having connection with a condenser 20 consisting of a coil 21. A check valve 22 is provided in the pipe 18 and a similar check valve 22^a is provided in the pipe 18^a, the said check valves being adapted to prevent the ammonia from the chambers 15 of the tanks 10 and 11 from passing backwardly into the tanks after the same has been forced into the pipes 18 and 18^a. A refrigerant receiving or storage tank 23 is provided, having connection with the condenser 20 through a pipe 24 and said tank 23 is connected to a freezing tank 25 by means of a pipe 26 provided with an expansion valve 27, adapted to regulate the flow of the liquid refrigerant to the freezing or expansion coil 28 in the tank 25. The coil 28 is connected at one end with the pipe 26 and the other end of the coil 28 is connected to a pipe 29 constituting a low pressure pipe, the said pipe 29 being provided with a controlling valve 30 and a pressure gage 31. The low pressure pipe 29 terminates in two oppositely extending arms 32, 32^a, each having connection with the lower ends of the chambers 15 through the cooling chambers 14 of the respective tanks 10 and 11. The arms 32 and 32^a are provided with the usual check valves 33 and controlling valves 34 as will be seen by referring to Fig. 1.

Secured to the arms 32 and 32^a at their lower ends and extending inwardly into the chambers 15 are circulators 35, one of the said circulators being secured to each of the arms 32, 32^a. Each of the said circulators 35 consists of a tubular body 36 bent to conform to the inner peripheral surface of the chambers 15 and the said body is provided with a series of spaced inclined apertures 37, shields 38 having substantially a frusto-conical shape being secured to the body 36, and extending rearwardly therefrom adjacent the apertures 37 as shown in Figs. 5 and 6. Expanded upwardly through the heads 16 of the tanks 10, 11 and having connection with the chambers 15 are pipes 39, 39^a respectively, each hav-

ing a pop valve 40 mounted at the upper end thereof. Connected to the pipe 39 below the pop valve 40 is a pipe 41 having its other end connected to the pop valve 40 on the pipe 39^a and connected to the pipe 39^a is a pipe 41^a having its other end connected to the pop valve 40 on the pipe 39. Gages 42 are mounted on the tanks 10 and 11, and extended upwardly from each of the heads 16 of the tanks 10 and 11 are thermometers 43 and pressure gages 44, the said thermometers and pressure gages each being connected with the chambers 15 of the respective tanks 10 and 11 to indicate the temperature of the ammonia contained in the chambers and the pressure of the ammonia.

25 A water supply 45 has connection with arms 46, 46^a the arm 46 being connected with the cooling chamber 14 of the tank 10 and the arm 46^a being connected with the cooling chamber 14 of the tank 11, the said arms 46, 46^a being each provided with controlling valves 47.

Extending into the tanks 10 and 11 is a pipe 48 having connection with heating coils 49 mounted to encircle burners 50 connected with fuel supply pipes 50', the said heating coils terminating in pipes 50^a connected to a combined charging and drain pipe 51, valves 52 being provided to control the supply of ammonia to the heating coils and tanks and a valve 53 being provided in the pipe 48 to control the supply of ammonia to either of the tanks. In practice, each tank 10 and 11 is supplied with aqua ammonia up to a desired level indicated by the gage 42, this being effected either by opening one of the valves 52 and supplying water charged with the ammonia gas through the pipe 51 and associated coil to the tank connected therewith, or by first feeding the water to the tank through the connections described and then supplying gas through the same connections until the water absorbs the proper amount of gas, when the valve 52 is closed. Assuming that both tanks are properly charged at the outset of the operation, and that the tank 10 is first set into action, it will be understood that the associated coil 49 is heated from the coacting burner 50, thus heating the water in said coil which is in open communication with the tank 10, a circulation of the water through the coil between the tank and coil being set up as in the single pipe circulating systems, thereby heating the body of aqua ammonia in the tank 10. When the water in the tank 10 is heated to the proper temperature to drive off the absorbed gas, the open valve 52 is closed, and the ammonia gas in practically an anhydrous condition passes to the condenser in which, owing to the high pressure due to the heat applied

and the cooling by the water flowing over the condenser, the ammonia is condensed into liquid form. This liquid passes to the storage receptacle 23, from which it flows through the expansion or regulating valve 27 into the freezing coil 28 on the low pressure side of the system and is evaporated by the heat received from the substance to be cooled, and takes up or absorbs such heat in the well known manner. The ammonia gas resulting from this evaporation passes back through the pipe 29 and open valves 30 and 34 to the tank 11 and is absorbed by the water in said tank. When practically all of the absorbed ammonia has been driven off from the first tank, the second tank will have absorbed its quota. The heating means connected with the tank 10 is then cut out of action, and the heating means connected with the tank 11 set into action so that the gas absorbed by the water in the tank 11 will be evaporated and caused to flow under pressure to the condenser where it is liquefied and the refrigerating process above described is repeated. While the aqua ammonia in the tank 11 is being heated, cooling water is supplied to the tank 10 to reduce the temperature of the water therein, in order that such tank may perform its function as an absorber, it being understood, of course, that the tanks act alternately as stills and absorbers to maintain a continuity of the refrigerating operation, the heating devices being governed and the valves properly opened and closed to control the flow of the ammonia. When either tank is employed as an absorber, the low pressure gas flowing therein through the pipe 29 passes into the arm 32 and downwardly through the cooling chamber 14, after which it will flow into the circulator 35 and discharge into and circulates through the water contained in the chamber 15 of the tank. By the action of this circulator the ammonia is distributed throughout the body of water and rapid absorption action obtained.

As a means of preventing excess pressure in either of the tanks 10 or 11, thus inducing an expansion in one of the tanks, I have provided a safety device operable by means of the pop valves 40 and the pipes 41, 41^a connecting the said pop valves with the pipes 39, 39^a. If, for instance, an excess pressure of ammonia is generated in the chamber 15 of the tank 10, the pop valve 40, regulated to operate at a specified pressure will assume an open position, thus permitting the excess ammonia to pass through the pipe 41^a and into the chamber 15 of the tank 11, thus primarily employing the tank 11 as an absorbing apparatus and if for any reason an excess pressure is generated in the tank 11, a similar process of transformation as has been described will take place relatively

to the tank 10 by means of the pop valve 40 on the pipe 39 so that the pressure in both the tanks 10 and 11 will be substantially equal at all times, thus minimizing the danger of explosions and preventing the wearing out of one tank sooner than the other.

From the foregoing description it will be seen that my invention provides a refrigerating apparatus of the character described which is simple of construction, reliable and efficient in action and of an economical type.

It will be further seen that with my device the use of the usual large amount of interior piping is dispensed with and dangerous explosions are avoided by permitting any excess gas in one tank to flow into the other tank thus relatively equalizing the pressure in both tanks.

20. In the use of the circulators 35 I provide means whereby the usual noise occasioned by ammonia gas contacting with water is entirely dispensed with and a further provision of the circulators 35 is to impart to 25 the water contained in the producing tanks a circulation which enables the water to be more readily cooled by coming in contact with the sides of the casing 13 inclosed by the cooling chamber 14, thus obtaining a 30 high cooling efficiency for the absorbing liquid in the chambers 15.

Having thus fully described the invention, what I claim as new, is:—

1. In a refrigerating apparatus, a still-absorber, a refrigerating coil associated therewith, a condenser in the line of connection between the still-absorber and coil, a low pressure pipe for conveying the spent refrigerant from the coil and a circulator 35 within the still-absorber and communicating with said pipe, said circulator comprising a cylindrical conductor extending partially around the still-absorber and provided with a series of spaced inclined discharge apertures, and a conical shield secured to the circulator body and arranged to surround the apertures.

2. In a refrigerating apparatus, a still-absorber, a jacket surrounding the same and forming a cooling chamber, means for supplying a cooling agent thereto, a refrigerating coil, high and low pressure pipes connected with the coil and condenser in the high pressure pipe, an expansion valve in 55 said high pressure pipe between the condenser and coil, a circulator within the still-absorber and comprising a cylindrical body extending partially around the same, a pipe leading from the low pressure pipe through 60 said cooling chamber to said cylindrical

body, said cylindrical body being provided with inclined discharge apertures, and a rearwardly extending conical shield secured to the cylindrical body and surrounding said apertures.

3. In a refrigerating apparatus, the combination of a pair of still-absorbers, a refrigerating coil, a high pressure pipe, valved connections between said high pressure pipe and the respective still-absorbers, a condenser in said pipe, an expansion valve in said pipe between the condenser and coil, a low pressure pipe connected with the coil, valved connections between said low pressure pipe and the respective still-absorbers, vent pipes communicating with the still-absorbers, each provided with a safety valve, and a pipe connection between the safety valve of each vent pipe and the other vent pipe below the safety valve therein.

4. In a refrigerating apparatus, the combination of a pair of still-absorbers, a refrigerating coil, a high pressure pipe connected with the coil, valved connections between the high pressure pipe and the still-absorbers, a condenser in the high pressure pipe, an expansion valve in the high pressure pipe between the condenser and coil, a connecting means between the still-absorbers affording relief valved intercommunication for the passage of excess pressure from one to the other, cooling jackets surrounding the still-absorbers, pipes disposed within said jackets, circulators within the still-absorbers and communicating with said pipes, a low pressure pipe connected with the coil, and valved connections between said low pressure pipe and the last-named pipes.

5. In a refrigerating apparatus, the combination of a pair of still-absorbers, a refrigerating coil, high and low pressure lines, valved connections between the respective still-absorbers and the high and low pressure lines, whereby the still-absorbers may be alternately employed as stills and absorbers, in connection with a common refrigerating system, a water supply pipe connecting the still and absorbers, a controlling valve in said pipe, a main water supply pipe, valved branches connecting the same with said water supply pipe on opposite sides of said controlling valve, said branches having heating coils therein, and burners for heating said coils.

In testimony whereof I affix my signature in presence of two witnesses.

JOHN HAMERSLEY.
